Primary Examiner — Janice Seeger*(74) Attorney, Agent, or Firm* — Husch Blackwell LLP(57) **CLAIM**

The ornamental design for a portable tabletop, as shown and described.

DESCRIPTION

FIG. 1 is a top perspective view of a portable tabletop showing the new design;

FIG. 2 is a left side elevation view of the portable tabletop shown in FIG. 1;

FIG. 3 is a right side elevation view of the portable tabletop shown in FIG. 1;

FIG. 4 is a front elevation view of the portable tabletop shown in FIG. 1;

FIG. 5 is a rear elevation view of the portable tabletop shown in FIG. 1;

FIG. 6 is a top plan view of the portable tabletop shown in FIG. 1; and,

FIG. 7 is a bottom plan view of the portable tabletop shown in FIG. 1.

The broken lines are for environmental purposes only and form no part of the claimed design.
